INVENTOR

Thomas W. Bilello
By his Attorney,
Nelson M. Howard

UNITED STATES PATENT OFFICE.

THOMAS W. BILELLO, OF LONG ISLAND CITY, NEW YORK, ASSIGNOR, BY MESNE ASSIGNMENTS, TO UNITED SHOE MACHINERY CORPORATION, OF PATERSON, NEW JERSEY, A CORPORATION OF NEW JERSEY.

SOLE-CUTTING DIE.

1,343,383.

Specification of Letters Patent. Patented June 15, 1920.

Application filed February 14, 1917. Serial No. 148,601.

To all whom it may concern:

Be it known that I, THOMAS W. BILELLO, a citizen of the United States, residing at Long Island City, in the borough of Queens and State of New York, have invented certain Improvements in Sole-Cutting Dies, of which the following description, in connection with the accompanying drawings, is a specification, like reference characters on the drawings indicating like parts in the several figures.

This invention relates to improvements in dies for cutting sheet material and more particularly to dies such as those intended for cutting out the soles of boots and shoes from sole leather. Dies for this use are extremely heavy and their manipulation is fatiguing work for the operator.

Various attempts have been made heretofore to facilitate the handling of steel dies, for example it has been proposed to secure metallic flanges about the upper edge of the die or to corrugate its outer surface. While these expedients have proved more or less helpful they have still left much to be desired.

The present invention contemplates improvements designed further to relieve the operator and to eliminate a serious objection to which all dies heretofore known have been open, viz., the chilling and numbing of the operator's hands occasioned by the necessity of grasping firmly and continuously the cold metal surface of the die. The work of a sole cutting operator is at best a hazardous occupation and in spite of all the precautions heretofore taken the loss of an operator's finger occurs all too frequently. This danger is intensified under conditions when the dies are very cold so that the operator's hands become thoroughly chilled.

As herein shown it is proposed to secure to the outer surface of the die material which will afford a warm, clinging, pleasant surface to be grasped. Preferably the material of the covering is so molded as to afford outwardly projecting lifting surfaces arranged to overlie the thumb and forefinger and extending at its lower edge into proximity to the cutting edge of the die, thereby being interposed completely between the metallic walls of the die and the hands of the operator.

In addition to the advantages above dis-

cussed, the provision of gripping material such as has been described permits considerable saving in the finishing operations upon the die, in that it is no longer necessary to smooth and shape the outer surface and flange of the die where the die is to be grasped, the attached gripping material covering all such irregularities. In fact, these are of utility in that they coöperate with the molded plastic covering to retain it against displacement.

These and other features of the invention will be best understood and appreciated from the following description of a preferred embodiment thereof selected for purposes of illustration and shown in the accompanying drawings, in which—

Figure 1 is a view in perspective of a sole die;

Fig. 2 is a view of the die in cross section, and

Fig. 3 is a view in perspective of a portion of the molded covering material.

The die shown in Fig. 1 comprises a sole shaped frame having its upper edge flattened to receive the pressure of the press in which the die is to be used and a lower sharpened cutting edge 4. The inner wall of the die is substantially vertical but affording a slight clearance. Secured to the toe and heel ends of the die are flanges 8 and 10, generally triangular in cross-section and with their outer and downwardly disposed surfaces concaved. The flanges 8 and 10 are disposed slightly below the pressure receiving edge of the die and are secured in place by brazing or riveting.

In the illustrated die a sheet or band 12 of rubber or rubber composition is shown as molded upon the outer surface of the die being secured thereto by vulcanizing or cementing. The band 12 is molded not only to fit the configuration of the walls of the die but also to follow the concave contour of the flanges 8 and 10. The concave molded portion of the band 14 is shown in Figs. 2 and 3. At its upper edge the band extends flush with the upper faces of the flanges 8 and 10 and at its lower end it terminates substantially coincident with the beveled surface of the cutting edge, being itself correspondingly beveled.

It will be apparent that the band 12 affords a downwardly projecting concave lift-

ing surface adjacent to its upper edge which will overlie the thumb and forefinger of the operator's hand while at the same time the lower portion of the band is interposed between the operator's hands and the wall of the die. While it is advantageous in a small die that the band 12 shall extend continuously above the die, it will be apparent that in many cases the band need not extend farther than the ends of the flanges 8 and 10. It is further within the scope of the invention to omit the metallic flanges entirely if so desired in which case it would be necessary merely that the molded portion 14 of the band should be stiff enough to support the weight of the die. Rubber or rubber composition is the best material now known to me for use as the material of the band but any other plastic compound or material such as cork having the desired characteristics may be used within the scope of the invention.

Having thus described my invention, what I claim as new and desire to secure by Letters Patent of the United States is:

- 25 1. A cutting die having a piece of sheet rubber secured to its outer surface between its pressure receiving and cutting edges and furnishing an unbroken surface to retain the grasp of the operator.
- 30 2. A cutting die having plastic material molded on its outer surface and extending from adjacent to the pressure receiving edge of the die, into proximity to its cutting edge, and terminating there in a beveled surface.
- 35 3. A sole cutting die comprising a sole-shaped frame having one edge sharpened for cutting and the other flattened to receive pressure, metallic flanges projecting outwardly from the sides of the die below its pressure receiving edge, and a broad continuous band of rubber secured to the outer surface of the die and concavely curved beneath the metallic flanges.
- 40 4. A sole cutting die having projecting flanges at its ends disposed adjacent to its upper edge, yielding plastic material secured to the outer face of the die, covering the lower surfaces of the flanges and extending into proximity to the cutting edge of the die.
- 45 5. A sole cutting die having projecting

flanges with concave lower surfaces, and yielding plastic material secured to the outer face of the die and being molded to the concave surfaces of the flanges, said plastic material extending continuously from the plane of the upper faces of the flanges into proximity to the cutting edge of the die.

6. A sole cutting die having secured to its opposite ends yielding plastic material so molded as to afford outwardly projecting lifting surfaces merging by concave surfaces into a portion disposed substantially parallel with the walls of the die and terminating in proximity to the cutting edge of the die.

7. A die adapted for manipulation by an operator and having secured upon the surface by which it is grasped an unbroken layer of a heat insulating substance tending to adhere to the hands of the operator.

8. A die having an unfinished surface, and a covering of a plastic material upon said surface co-operating with the irregularities thereof.

9. A die having an irregular surface, and a layer of rubber molded upon said surface in engagement with its irregularities.

10. A die adapted for manipulation by an operator and having irregularities upon the surface over which it is grasped, and a layer of a heat insulating plastic material engaging the irregularities of the surface and tending to adhere to the hands of the operator.

11. A die having a wall by which it may be grasped when in action and including a considerable mass of metal, said wall during the use of the die extending generally in a vertical direction and being formed at its lower portion with a cutting edge and at its upper portion with a pressure-receiving surface, and yieldable heat-insulating material carried by the die wall and furnishing an unbroken layer between its metal and the hands of the operator, thereby preventing them from becoming numb by the absorption of heat by the mass of metal and slipping above the pressure-receiving surface.

In testimony whereof I have signed my name to this specification.

THOMAS W. BILELLO.
